PUMP LOCKING DEVICE

Conrad R. Buchet, Long Beach, Calif., assignor to
Repal Brass Mfg. Co., Los Angeles, Calif.

Application January 25, 1933, Serial No. 653,522

3 Claims. (Cl. 103—28)

My invention relates to improvements in pump flow control means and has particular reference to oil and gasoline pumps, such as are used at automobile service stations.

5 Briefly stated, the invention has for its primary object to provide a highly simplified device of this character which will be controlled by the level of the fluid being pumped, and which will operate to shut off the flow of fluid when it falls below a certain level in the tank, in this way assuring the prevention of "short measure".

Another object of the invention is to provide operating means including a cup element submerged in the fluid, and which when the fluid 15 drops below a certain level by reason of weight of the fluid in the cup will cause operation of the shut-off to prevent flow of fluid.

The invention also resides in certain novel features of construction, combination and arrangement, all of which will be readily apparent to those skilled in the art upon reference to the accompanying drawing in connection with the detailed description to follow.

25 It is to be understood that the drawing illustrates what now appears to be a preferred form of the invention. However, of course, various changes may be made within the spirit and scope of the subject matter claimed hereinafter.

30 In the drawing,

Figure 1 is a vertical sectional view of a pump cylinder and piston, and illustrating one form of my invention;

35 Figure 2 is a similar view illustrating a modified form of my invention;

Figure 3 is a fragmentary vertical section of a slight modification.

Referring specifically to the drawing, wherein the same reference characters have been used to 40 designate the same parts in all views, numeral 3 denotes the cylinder of the conventional gasoline or oil pump such as is used at service stations. This cylinder will of course be located in the usual tank C and provides the piston chamber 3^a within which works the piston which is generally designated as at 4 and is provided by the cups 4^a, 4^b whose bottom portions are clamped together by the nuts 6 on the connecting rod 5.

50 The piston 4 is provided with the check valves which comprehend the casings 7 adapted to be inserted through registering holes in the bottom of the cups 4^a, 4^b and to be held in place by means of the flanged plugs 7^c which thread into the lower end of the valve casings 7 and draw

the flanges 7^b thereof tightly into contact with the top surface of the upper cup.

The cap 7^c provides the fluid inlet 8 and the seat for the ball valve 9, while the casing 7 provides the fluid outlet 7^a above the bottom surface of the cup 4^b. The operation of the pump is, of course, familiar and no special reference thereto is necessary.

Still referring to Figure 1, it will be noted that the cylinder 3 is provided at one side with the 10 bracket 10 which is secured in place as indicated at 11. Such bracket 10 provides the bearing 12 for the pintle or pivot element 13 of what is substantially a bell crank having the arms 14, 14^a. The arm 14 of the bell crank terminates in a 15 float cup 15 while the arm 14^a has its lower end provided with a forwardly extending arm 16 which is or may be curved downwardly slightly as shown, although it may be plane or substantially so.

The cylinder 3 is provided with a hole 17 and, as shown in Figure 1, the flange of the piston cup 4^a has a hole 18 which is adapted to register with the hole 17 so that, upon occasion, the end of the forwardly extending arm 16 can be projected through the registering holes 17, 18 to 25 lock the piston 4 against movement.

A spring 19 on the curved or arcuate arm 16 bears against the cylinder 3 at one end and against the arm 14^a at the other end. The 30 strength of this spring is such that it will prevent the arm 16 from being projected through the hole 17 in the cylinder except when the level of fluid in the tank is such as to allow the cup 15 to drop to the dotted line position.

It is important to remember that the cup 15 will ordinarily be submerged in the fluid of the tank which surrounds the cylinder 3 and naturally there will be fluid in the cup 15. However, so long as the fluid in the tank remains above the 40 cup 15, the cup will be substantially floated and this, with the action of the spring 19, will prevent the end of 16 from extending through the hole 17 of the cylinder. However, when the level of fluid in the tank falls the weight of the cup full of oil 45 will be sufficient to over balance the spring and the end of the forwardly curved arm 16 will be engaged through the hole 17 of the cylinder, so as to bear against the piston, and when the piston comes to the position shown in Figure 1 it will 50 pass through the hole 18 to lock the piston against further movement until such time as the tank has been resupplied with fluid.

In this way it is, of course, impossible to pump "short measure" and the purchaser of gasoline or 55

oil is assured of receiving the quantity purchased. These pumps are of course arranged to pump an exact number of gallons or other quantity in accordance with a predetermined movement of the 5 piston or its operating means.

Figure 2 illustrates a slightly modified form of the invention wherein the cylinder 20 provides the piston chamber 21 within which works piston 22 which is shown adjacent the lower end of the cylinder which will of course be submerged in the 10 fluid tank as mentioned in connection with Figure 1.

I have illustrated the cylinder 20 as provided with the bracket 23 secured in place by suitable 15 fasteners 24. Such bracket 23 provides at its outer end a bearing 23^a for the pivot or other element 25 of the rockable arm 26 whose outer end is provided with the cup 28 while its inner end is provided with the cup-like closure 27 for the 20 lower end of the piston chamber 21.

Naturally when the fluid in the tank is above 25 the level of the cup 28, the weight of the cup-like closure 27 for the end of the cylinder 21 will be sufficient to hold the same in the dotted line position of Figure 2. However, when the level of 30 fluid in the tank falls below the lubricant containing cup 28, the weight of the fluid in such cup and also of course the weight of the cup will cooperate to over balance the closure weight 27 and the same will be forced to the full line position to 35 close the end of the cylinder 21 and that prevents the entry of fluid thereinto and of course prevents operation of the piston 22 because of the vacuum that will be created below such piston 22.

35. The simplicity and other advantageous features of my pump will be readily appreciated. For instance, in the structure shown in Figure 1, I eliminate the necessity for any special construction of the piston 4. It is not necessary to provide the 40 piston 4 with any lugs or catchers to engage a latch; and furthermore, there is no latch element within the piston chamber except when it is desired to lock the piston. Still referring to Figure 1, from the fact that the arm 16 is not turned 45 in the arc of a circle whose center is pivot 13, it will be apparent that if the arm 16 should be projected through the hole 17 into the wall of cylinder 3 when the piston were at its upper position that movement of the bevelled portion of the 50 cup 4^a of the piston against the arm 16 would simply serve to rock it out of the way, so that the end would simply bear against the side of the piston 4 until the opening 18 was reached.

The structure of Figure 2 eliminates the necessity for the locked arm or element 16. It, as 55 stated, also incorporates a novel actuating cup 28.

The structure of Figure 3 shows a further slight modification wherein the valve bushing 30 secures an L-bracket 31, whose depending arm 31^a has

the latch recess 32 for receiving the latch end 34^a of the bell crank 34, which is pivoted as at 35 in a second bracket 36 welded or otherwise secured to the pump shell wall 37.

The outer end of bell crank 34 has a cup 38 like 5 28, Figure 2, and no novelty is claimed for the valve 39 per se.

A coil or other spring 40 secured at one end to 10 37 and at the other end to bell crank 34 tends to hold latch 34^a out of latching position so that the piston may be freely moved up and down until the fluid level drops below a predetermined point. Then the weight of fluid in cup 38 actuates latch 34^a to latching position.

Having thus described my invention, what I 15 claim as new is:

1. In a dispensing unit including a fluid container, a pump structure comprising a cylinder and piston mounted in said container, said cylinder and piston having holes adapted to come 20 into alignment, flow control mechanism for the pump comprising a bell crank pivoted to the wall of the cylinder, a float cup secured to one arm of said crank, a latch element at least in part carried by the other arm of said crank, said latch element adapted to engage said holes when aligned when the fluid in said container falls below a certain level, and a spring interposed between 25 said second mentioned arm and cylinder and tending to maintain said latch disengaged 30 from said piston hole.

2. In a dispensing unit including a fluid container, a pump structure comprising a cylinder and piston mounted in said container, said cylinder and piston having holes adapted to come 35 into alignment, flow control mechanism for the pump comprising a bell crank pivoted to the wall of the cylinder, a float cup secured to one arm of said crank, a latch element at least in 40 part carried by the other arm of said crank, said latch element adapted to engage said holes when aligned when the fluid in said container falls below a certain level, and yielding means 45 tending to maintain said bell crank in position to render said latch inoperative.

3. In a dispensing unit including a fluid container, a pump structure comprising a cylinder and piston mounted in said container, said cylinder and piston having holes in the sides thereof adapted to come into alignment, flow control 50 mechanism for the pump comprising a bell crank pivoted to the wall of the cylinder, a float cup secured to one arm of said crank, a latch element at least in part carried by the other arm of said crank, and said latch element adapted to 55 engage said holes when aligned when the fluid in said container falls below a certain level.

CONRAD R. BUCHET.
